UNITED STATES PATENT OFFICE.

EDWIN R. HISEY, OF GUERNSEY, WYOMING, AND OLIVER C. PATTON, OF DENVER,
COLORADO.

STOVEPIPE FASTENER.

Application filed January 3, 1924. Serial No. 634,202.

To all whom it may concern:

Be it known that we, EDWIN R. HISEY and OLIVER C. PATTON, citizens of the United States, residing at Guernsey, in the county of Platte and State of Wyoming, and Denver, in the county of Denver and State of Colorado, respectively, have invented certain new and useful Improvements in Stovepipe Fasteners, of which the following is a specification.

This invention relates to an appliance for securing pipes in correspondingly formed passages and its object is to provide a simple and readily adjusted device for fastening a pipe in an opening in which it is inserted, by inwardly applied and outwardly directed pressure.

Our invention is particularly adapted for use in connection with smoke pipes of stoves and furnaces, at the point at which they enter the chimney flue, it being well known that the accidental displacement of the pipes at that point is a frequent occurrence which often results in serious damage to the building in which the pipes are installed, by the escape of smoke and fire.

The appliance consists of an expander of simple construction which is placed inside the stove pipe before it is inserted in the flue and which remains a permanent part thereof. The construction of the expander permits of its ready operation by a hand inserted in the pipe from the inner end thereof, and its action upon the inner surface of the pipe at different points of its circumference, causes the pipe to frictionally engage with the surface of the passage in which it is inserted with the effect that the pipe is securely locked against displacement.

It is an aim of our invention to construct the expander so that it may be produced at a very low cost, thereby permitting of its application to smoke pipes and other similar flues and conduits without material increase in the selling price thereof, and it will be apparent that although the application of our invention may increase the initial purchase price of the pipes, the increase is fully compensated by the reduced cost of installation since the use of the expander completely eliminates the provision of braces, wiring, cementing and other expedients now commonly used to hold the pipes

in constant and air-tight connection with the flues in which they are inserted.

An embodiment of our invention has been illustrated in the accompanying drawings in which similar characters of reference designate corresponding parts throughout the several views and in which—

Figure 1 represents a sectional elevation of a flue, and a therewith connecting pipe to which our invention is applied;

Figure 2, a much enlarged section taken on the line 2—2, Figure 1;

Figure 3, a fragmentary section along the line 3—3, Figure 2; and

Figure 4, a similar section taken on the line 4—4, Figure 2.

Referring to the drawings, the reference character 5 designates an upright flue structure made of brick or other suitable building material and having a lateral inlet opening 6 for its connection with the sheet metal pipe 7 of the furnace, stove or other heating apparatus.

The inlet opening of the flue is usually lined with a sheet metal "thimble" 8 and the end of the pipe which fits inside the thimble, has a bead 7^a to limit its inward movement.

The expander which secures the pipe inside the opening in accordance with our invention, comprises two complementary sections 9 which are connected by a rotary bolt 10.

The sections each have two diverging legs 9^a connected by an intermediate part 9^b to which the bolt is applied and the ends of the legs are concaved to provide pointed teeth 9^d for engagement with the surface of a conduit to which the expander is applied.

The connections between the legs have central screw-threaded openings and the two screw-threads of the sections of each expander are oppositely directed to provide for the application of a bolt having a right-hand screw thread and a lefthand screw thread respectively at opposite ends thereof.

A hand-lever 12 passes through a central opening of the screw to facilitate its rotation, both ends of the lever having been enlarged as at 13 to prevent its disconnection from the bolt.

In the operation of our invention, the pipe section 7 equipped with the expander, is inserted in the inlet opening of the flue

until the bead on the section engages the outer surface of the same. The operator then inserts a hand into the pipe section through the inner end thereof and by manipulation of the lever 12, turns the bolt 10 and thereby causes the sections of the expander to further separate until the pipe is clamped tightly in the opening of the flue.

It will be apparent that the pipe thus secured is easily removed for cleaning or repairs by a few turns of the bolt in the opposite direction.

Having thus described our fastening appliance, we desire it understood that changes in details of construction of its cooperating parts may be made within the spirit of our invention as defined in the following claims.

What we claim and desire to secure by Letters Patent is:

1. A flue fastener comprising two rigid members having a plurality of separated prongs adapted to indent the inner surface of a flue in circular alinement, and manual means to enlarge the circle of the prongs by separate adjustment of the members.

2. A flue fastener comprising two members reversely positioned with relation to each other in a common plane and each composed of two rigidly connected, divergent and rigid legs the ends of which are pointed to indent the inner surface of the flue, and

manual means associated with the connections of the members for their simultaneous separative adjustment.

3. A flue fastener comprising two members reversely positioned with relation to each other in a common plane and each composed of two diverging rigid legs and an integral connection between adjacent ends thereof, provided with a central threaded aperture, and a bolt having right and left hand screw threads cooperatively engaging in said apertures, the free ends of the legs being pointed to indent the surface of the flue when the members are forced apart by rotation of the bolt.

4. The combination with a flue, of a fastener comprising two members each having two rigidly connected, rigid and diverging legs the free extremities of which have points adapted to indent the metal of the flue, the members being disposed in a common plane with the points of their legs engaging the inner surface of the flue in circular alinement, and manual means associated with the connections of the members to enlarge the circle of their prongs by simultaneous outward adjustment of the members.

In testimony whereof we have affixed our signatures.

EDWIN R. HISEY.
OLIVER C. PATTON.
